GAME-PIECE OR SIMILAR ARTICLE

Arthur J. Guest, Pomona, Calif.

Application March 22, 1955, Serial No. 35,159

Term of patent 14 years

(CL. D34—5)

Fig. 1.

Fig. 2.

Fig. 3.

Fig. 1 is a plan view of the game-piece or similar article, showing my new design.

Fig. 2 is a side view.

Fig. 3 is a bottom view.

The drawing figures are lined to indicate color contrast. This application is a continuation-in-part of my application, Serial No. D. 30,196 filed April 26, 1954, now abandoned.

I claim:

The ornamental design for a game-piece or similar article, as shown and described.
